UNITED STATES PATENT OFFICE.

WILLIAM SCHWAGERMANN, OF YONKERS, NEW YORK, ASSIGNOR TO WARD LEONARD ELECTRIC COMPANY, A CORPORATION OF NEW YORK.

RHEOSTAT.

1,374,241.

Specification of Letters Patent. Patented Apr. 12, 1921.

Application filed June 27, 1917. Serial No. 177,245.

To all whom it may concern:

Be it known that I, WILLIAM SCHWAGERMANN, a citizen of the United States, residing at Yonkers, in the county of West Chester and State of New York, have invented certain new and useful Improvements in Rheostats, of which the following is a specification.

The principal object of my invention is to provide a new and improved method for conveniently and economically manufacturing a rheostat. Another object of my invention is to provide a simple serviceable rheostat, that is the product of such a method. Another object of my invention is to provide a contact button for a rheostat that can readily be brought in registry with other contact buttons, and that shall be convenient and inexpensive to manufacture. All these objects and others will be made apparent in the following specification and claims taken in connection with the accompanying drawings. In these drawings I have shown one specific device in which my inventive idea may be embodied and I now proceed to describe the particular apparatus shown in the drawings.

Figure 1 is an elevation of my improved rheostat viewed edgewise with respect to the plane of the contact buttons;

Fig. 2 is a rear elevation of the same;

Fig. 3 is a view of a blank from which one of the contact buttons may be formed;

Fig. 4 is a perspective view of a contact button after it has been shaped from the blank shown in Fig. 3;

Fig. 5 is a view of one of the contact buttons after it has been fixed to the insulating support therefor;

Fig. 6 is a corresponding view after the button has been upset according to the method herein described;

Fig. 7 is an enlarged fragmental rear elevation showing the resistance elements exposed to view, and

Fig. 8 is an elevation of apparatus which may be used to bring the contact buttons in registry.

A cast iron disk 11 has a peripheral lip 12 around the rear face and also has three posts 13 equally spaced around its margin by which it may be attached to the wall indicated by the reference numeral 14. A shaft 15 is rotatably mounted axially with respect to the disk and carries a knob 16 on

its outer end by which it may be rotated by hand for adjusting the rheostat. This shaft 15 also carries an index 17, on the outer side of the disk 11, and the rheostat contact arm 18, on the inner side, whose end 37 has a member adapted to engage the contact buttons 20 in succession.

The back face of the cast iron disk 11 within the rim or flange 12 is coated with a layer of insulating enamel 19 which is baked; then the resistance wire 22 is assembled with the contact buttons 20 as shown in Fig. 7 and placed on the enamel coat 19. Then another coat of enamel 21 is applied which overlies the toes 29 and 30 of the contact buttons 20, thus supporting them firmly in position. It will be seen that the resistance wire 22 lies between the two enamel coats 19 and 21 and is thus effectively insulated, but at the same time good facility is afforded for dissipating heat from the wire 22 by conduction and radiation.

Insulated binding posts 23 and 24 are provided to which the circuit connections can be made and from these one conductor 25 extends between the two coats of enamel 19 and 21 to the end contact button of the series. Also from the binding post 24 another conductor 26 lying between the two coats of enamel 19 and 21 extends to the insulated iron disk 34 which lies against the enamel coat 21, and makes conductive contact with arm 18.

The contact buttons, each represented generally by the reference numeral 20, are formed from blanks such as shown in Fig. 3 each cut from suitable sheet brass. Each blank, as shown in Fig. 3, has two slots 27 and is notched near one end as indicated at 28. These blanks as shown in Fig. 3 are then given the shape shown in Fig. 4 by which their end portions 29 and 30 lie in the same plane and are adapted to go against the plane surface on which they are to be supported. The extremity of the toe 30 beyond the notches 28 is bent over and pinched down on the resistance wire 22. The intermediate part 33 of the button 20 lies in a plane parallel to the plane of the two toes 29 and 30 and is adapted to be engaged by the end of the moving contact arm 18.

After the iron disk 11 has had assembled therewith the two coats of enamel 19 and 21 and the resistance elements 22 and the contact buttons 20, it may happen that the

outer surfaces 33 of the contact buttons 20 will not all lie precisely in one plane. One reason why there may be such deviation would be because the casting 11 may not be perfectly true; another reason may be that the thickness of the enamel coat 19 may not be absolutely uniform. Accordingly, I lay the disk 11 down on the anvil 35 and bring the cylindrical die 36 down in engagement

10 with the faces 33 of the contact buttons 20 so as to press all these buttons 20 down from the shape shown in Fig. 5 to that shown in Fig. 6. This brings all the faces 33 in accurate registry in one plane so that the end 15 of the contact arm 18 may sweep smoothly over the buttons 20 in the adjustment of resistance by means of the rheostat.

After the cylindrical die 36 has been pressed down it may be given a slight degree 20 of rotation around its axis by which its lower surface will slightly scratch the surfaces 33 of the buttons 20 in a circumferential direction. Thus, on removal of the die 36, a glance at the buttons 20 will give 25 assurance by the slight scratches that will be shown on the surfaces 33 that the die has indeed engaged all of them and that they have all been brought into proper registry in a single plane.

30 The shape of the button, as shown in Fig. 5, and the formation and location of the slots 27 insure that upon direct pressure against the face 33 the deformation will be as shown in Fig. 6. Also the fact that the 35 slots 27 extend into the toes 29 and 30 of the button gives a more effective engagement of the enamel coat 21 so that it holds the button more firmly in position.

By turning the handle or knob 16 manually, the arm 18 will be swept over the successive contact buttons 20 passing smoothly from one to the next and adjusting the amount of resistance effectively included between the binding posts 23 and 24.

45 Among the advantages of my improvement are that my contact buttons do not require an excessive amount of material, thus avoiding expense for material and my method of bringing their outer surfaces into registry involves no such waste as there would be if they were ground off. Also my method of adjustment herein disclosed is very quick and simple and involves small labor cost.

55 It will be understood that modifications of the foregoing disclosure may be made that will be included within the scope of my invention.

I claim:

60 1. In the method of adjusting a rheostat so that its arm may smoothly engage the contact buttons in succession, the step which consists in deforming these contact buttons simultaneously and thereby bringing their surfaces into registry.

2. In the method of adjusting a rheostat so that its arm may smoothly engage the contact buttons in succession, the step which consists in applying a single die with a plane face adapted to engage all said buttons and thereby deforming the buttons until the die comes into engagement with all of them thus leaving them all with their engaged surfaces in registry in a single plane.

3. In the method of adjusting a rheostat 75 having contact buttons which when assembled at a certain stage have their surfaces somewhat out of registry, the step which consists in applying a die and thereby deforming the buttons until they are brought 80 into proper registry with one another.

4. In the method of adjusting a rheostat so that its arm may smoothly engage the contact buttons in succession, the steps which consist in deforming these contact 85 buttons simultaneously by the application of a single die and thereby bringing their surfaces into registry and then rotating the die through a certain angle to mark the contact buttons and thereby give indication on removal of the die as to whether it has effectively engaged all said buttons.

5. A rheostat comprising a support, a row 95 of contact buttons carried thereby, resistance elements associated therewith, and an arm adapted to engage said buttons successively, said buttons being of malleable material and deformed so as to bring their surfaces into registry in a single plane for engagement by said arm.

6. A rheostat comprising a support, a row of contact buttons carried thereby, resistance elements associated therewith, and an arm adapted to engage said buttons successively, said buttons being of malleable sheet metal 105 and individually deformed so as to bring their surfaces into registry in a single plane for engagement by said arm.

7. A rheostat comprising an iron plate, a coat of insulating enamel thereon, a row of contact buttons and associated resistance elements mounted on said enamel coat, another enamel coat over said resistance elements and parts of said buttons to retain them in position, and an arm adapted to engage said buttons successively, the exposed parts of said buttons being of malleable sheet metal and individually deformed after assembly as aforesaid so as to bring their surfaces in accurate registry in one plane to be engaged 110 by said arm.

8. A rheostat contact button consisting of a piece of sheet metal with its end portions lying in a plane and adapted to be secured to a support and with its intermediate portion 115 displaced out from the plane of the end portions and lying in a parallel plane.

9. A rheostat contact button consisting of a strip of sheet metal with a longitudinal slot cut in each end portion and with its 120

extreme end portions lying in one plane for engagement with a support and its intermediate portion offset in a parallel plane.

10. A rheostat contact button consisting of a strip of sheet metal with its two end parts lying in one plane for engagement with a support and one extreme end bent and pinched over a resistance wire, the intermediate part of said strip of metal being offset and lying in a parallel plane.

11. A rheostat contact button consisting of a strip of sheet metal with its end portions lying in a single plane for engagement with a support, its middle portion being offset in a parallel plane, and the parts joining the end portions with the middle portion being curved convexly toward each other.

12. A rheostat contact button consisting of a strip of sheet metal with its end portions lying in a single plane for engagement with a support, its middle portion being offset in a parallel plane, and the parts joining the end portions with the middle portion being curved convexly toward each other and slotted longitudinally.

13. A rheostat contact button consisting of a strip of sheet metal with its end portions lying in a single plane for engagement with a support, its middle portion being offset in a parallel plane, and the parts joining the end portions with the middle portion being curved convexly toward each other and slotted longitudinally, the slots extending into the said end portions.

35 14. A rheostat contact button consisting of a piece of malleable sheet metal having a part adapted to engage a support, a part offset therefrom, and another part joining them and adapted to be permanently deformed by pressure on the offset part toward the support.

15. A rheostat contact button consisting of a strip of sheet metal with its end portions lying in a single plane for engagement with a support, its middle portion being offset in a parallel plane, and the parts joining the end portions with the middle portion being curved.

40 16. A rheostat contact button consisting

of a strip of sheet metal with its end portions lying in a single plane for engagement with a support, its middle portion being offset in a parallel plane, and the parts joining the end portions with the middle portion being curved and slotted longitudinally, the slots extending into the said end portions.

17. A rheostat contact button consisting of a strip of sheet metal with its end portions lying in a single plane for engagement with a support, its middle portion being offset in a parallel plane, and the parts joining the end portions with the middle portion being curved and slotted longitudinally.

18. A rheostat contact button consisting of a piece of malleable metal having a part adapted to engage a support, a part offset therefrom, and another curved part joining them and adapted to be permanently deformed by pressure on the offset part toward the support.

19. A rheostat contact button comprising a flat head and an oblique supporting element, the latter being adapted to be deformed so as to bring the head of the button in registry with the heads of other buttons.

20. A rheostat contact button comprising two parallel parts and a connecting part, one of the parallel parts serving as the contact head, the other parallel part serving for attachment to a support and the connecting part being capable of deformation to bring the head in registry with the heads of other buttons.

21. In the method of adjusting a rheostat so that its arm may smoothly engage the contact buttons in succession, the step which consists in deforming the most prominent buttons at one operation after assembling so as to bring all their contact surfaces in registry with the least prominent of them.

22. In the method of adjusting a rheostat so that its arm may smoothly engage the contact buttons in succession, the step which consists in deforming the more prominent buttons in proportion to their degree of prominence so as to bring their contact surfaces in registry.

WILLIAM SCHWAGERMANN.
